Primary Examiner — Selina Sikder(74) *Attorney, Agent, or Firm* — Studebaker & Brackett PC(57) **CLAIM**

The ornamental design for a multi remote controller as shown and described.

DESCRIPTION

FIG. 1. is a perspective view of a multi remote controller showing my new design;

FIG. 2. is a front view thereof;

FIG. 3. is a rear view thereof;

FIG. 4. is a top plan view thereof;

FIG. 5. is a bottom view thereof;

FIG. 6. is a right side view thereof; and,

FIG. 7. is a left side view thereof.

The broken lines showing of the multi remote controller is included for the purpose of illustrating portions of the multi remote controller and forms no part of the claimed design.

1 Claim, 7 Drawing Sheets(56)
